UNITED STATES PATENT OFFICE.

WILLIAM OTTO, OF ALGOMA, WISCONSIN.

MANURE LOADER.

Application filed May 25, 1922. Serial No. 563,497.

To all whom it may concern:

Be it known that I, WILLIAM OTTO, a citizen of the United States, residing at Algoma, in the county of Kewaunee and State 5 of Wisconsin, have invented certain new and useful Improvements in Manure Loaders, of which the following is a specification.

The invention relates to a loading machine and more particularly to the class of 10 manure loaders.

The primary object of the invention is the provision of a machine of this character, wherein a pile of material such as manure or the like can be conveyed into a wagon or 15 other conveyance without requiring manual labor, the machine being adjustable to permit the conveyor mechanism to be shifted relative to the pile as the bulk thereof decreases, and thus in this manner avoid the 20 constant changing of the position of the machine in its entirety and the material continuously fed to the wagon or other receiving vehicle until the mass or pile has entirely diminished.

Another object of the invention is the provision of a machine of this character, wherein the conveyor mechanism can be extended or retracted and likewise the feed forks can 25 be adjusted to regulate the extent of throw or movement thereof, thus it being seen that said forks will be operable on the maximum of the pile of material at one setting of the machine.

A further object of the invention is the 30 provision of a machine of this character which is novel in form, construction and operation so as to render the same effective for the handling of piled material irrespective of the volume or height thereof.

A still further object of the invention is the provision of a machine of this character which is comparatively simple in construction, readily portable, thoroughly reliable and efficient in its purpose, strong so as to 35 sustain maximum loads and inexpensive to manufacture as well as durable.

With these and other objects in view, the invention consists in the feature of construction, combination and arrangement of parts, 40 as will be hereinafter fully described, illustrated in the accompanying drawings, and pointed out in the claims hereunto appended.

In the accompanying drawings:

Figure 1, is the side elevation of a ma-

chine constructed in accordance with the invention showing diagrammatically a wagon body in end elevation for receiving a load from the machine.

Figure 2, is a top plan view of the ma- 60 chine.

Figure 3, is a rear elevation.

Figure 4, is a vertical longitudinal sec- 65 tional view through the machine.

Figure 5, is a sectional view on the line 65 5-5 of Figure 2.

Similar reference characters indicate cor- 70 responding parts throughout the several views in the drawings.

Referring to the drawings in detail, A, 75 designates generally the bed of a wheel truck having the front guide wheels 10, and rear ground wheels 11, so as to render said truck mobile, the front guide wheels 10, being fitted to an axle B, provided with a draft tongue 12, for the hitching of draft animals thereto, whereby said truck can be drawn from one locality to another. Adapted to be mounted on the forward part of the bed A, of the truck is a suitable gas 80 engine 13, constituting the power plant of the machine.

Mounted upon the bed A, of the truck at the rear end portion thereof is a circular grooved track 14, in which travel the bearing rollers 15, for a turn table 16, superposed above the bed A, for supporting the loading mechanism of the machine hereinafter fully described.

Secured to the under side of the turn 90 table 16, is a circular rack gear 17, with which meshes a rack pinion 18, fixed to the turning shaft 19, journaled centrally of the bed A, and this shaft is disposed longitudinally in a forward direction to the bed and 95 has fixed to its forward end a hand operable wheel 20, to be manually actuated for the rotation of turn table 16, as will be apparent.

Extending vertically and centrally through the turn table is a driven shaft 21, 100 the lower end being fitted with a beveled pinion 22 meshing with a beveled gear 23, fixed to the inner end of a horizontal shaft 24, journaled transversely in the truck bed A, with its outer end projected beyond one 105 side of the latter and having fixed thereto a belt pulley 25 over which is trained a belt 27, driven from the power pulley C, of the engine 13, as is shown in Figure 1, of the drawings.

Mounted upon the turn table 16, is a support 28, for a rearwardly inclined stationary conveyor frame 29, having mounted therein in the lower portion of the same an endless conveyor 30, provided with cross flights 31, at determined intervals thereof, and this conveyor has its lower stretch movable in the support 28, over idle sprockets 32, while the forward power shaft 33, for 10 the conveyor 30, has fixed thereto, a sprocket wheel 34, over which is trained an endless sprocket chain 35, the same being also trained over a sprocket wheel 36, fixed to a power transmission shaft 37, journaled 15 transversely in the support 28.

The transmission shaft 37, is also fitted with a beveled gear 38, meshing with a beveled pinion 39, fixed to the upper end of the shaft 21, so that power from the engine 20 13, will be transmitted to the conveyor 30, for the driving thereof.

Mounted in the stationary conveyor frame 29, is a slidable conveyor frame 40 which is movable upon guide rollers 41, mounted in 25 the rear end of the conveyor frame 29, while suitably mounted at the forward end of the slidable conveyor frame 40, is a carriage 42, slidably fitted in slots 43, formed in opposite sides in the stationary conveyor frame 30 29, while upon the top edges of the sides of the latter frame 29 are toothed rack bars 44, with which mesh rack pinions 45, fixed to a counter shaft 46, suitably journaled upon the forward end of the slidable conveyor 35 frame 40, the shaft 46, being also fitted with a sprocket 47, over which is trained a sprocket chain 48, the same being also trained over a sprocket 49 on a hand wheel shaft 50, having a hand wheel 51, which is manually operated so that in this manner the slidable conveyor can be extended or retracted relative to the stationary frame 29, for a purpose presently described.

Arranged within the lower portion of the 45 slidable conveyor frame 40, is an endless conveyor 52, the same being trained over sprockets D, and E, respectively, which sprockets E, are carried on a forward power shaft 53, for driving said conveyor. The 50 shaft 53, is further provided with a sprocket wheel 54, meshing with a power sprocket chain 55, trained over sprocket gears 56 and 57, respectively, the shaft for the latter being fitted with a sprocket wheel 58, over 55 which is trained an endless sprocket chain 59, which is also trained over a sprocket wheel 60, on the power shaft 33, of the conveyor 30, so that motion from the latter will be transmitted to the conveyor 52.

The upper stretch of the chain 55, is held 60 in engagement with the gear 54, through the medium of a chain retaining device, in the form of spaced idle rollers 61, located on opposite sides of the point of engagement 65 of the gear 54, with the chain 55, the rollers

being journaled on a suitable bracket F, pivoted on the side of the frame 40, as shown in Figure 1, of the drawings.

On the conveyor frame 40, is a swinging top section 62, the hangers G, therefor being 70 journaled on the shaft H, from which point the section 62, swings. This section 62, has fitted thereon bearings 63, in which is journaled a cranked shaft 64, while spaced from these bearings 63, are slotted guides 65, secured to said section, and in these guides are slidably mounted cross-heads 66, to which are pivotally connected oscillating fork arms 67, which project beyond the rear end of the machine, and have fixed in 75 the outer ends thereof tines or forks 68, the same being detachably mounted on the arms 67 by means of fasteners 69.

The fork arms 67, are engaged in the cranks of the crank shaft 64, so that the same may alternately be moved up and down and in and out relative to the adjustable screen frame 40. The cranked shaft 64, has fixed at one end a sprocket 70, over which is trained a sprocket chain 71, the same being also trained over a sprocket 72 which is operated by a gear 73, meshing with a companion gear 74, operated by a sprocket 75 over which is trained a sprocket chain 76, the latter being also trained over a sprocket wheel 77, on the power shaft 53, for the conveyor 52, so that motion will be imparted to the crank shaft for operating the fork arms.

Connected to the swinging section 62, of the slidable conveyor frame 40, are vertically disposed rack members 78, with which mesh rack pinions 79, fixed to a shaft 80, journaled upon stationary uprights 81, rising from the rear end of the slidable conveyor frame 40, and this shaft has fixed thereto a sprocket gear 82, over which is trained an endless sprocket chain 83, the same being also trained over a sprocket gear 84, fixed to a hand wheel shaft 85, mounted in suitable bearings 86, on the frame 40, the shaft 85, being fixed with a hand wheel 87, so that when manually manipulated, the rack members 78, may be raised and lowered to vary the angular pitch of the swinging sections 62, and thereby properly positioned the forks 68, relative to a pile of material for the raking thereof into the adjustable conveyor frame 40, for the conveying of the load by the conveyor 52, into the stationary frame 29, and thence by the conveyor 30, into a wagon body 88, for the loading of the same.

The rack members 78, are held against the rack pinion 79, by means of guide rollers 89, suitably constructed and arranged on the standards 81, thus maintaining the rack members in meshing engagement with the rack pinions hereinbefore set forth.

Now from the foregoing description it

- will be clearly apparent that the loading machine has a maximum radius of action as by means of the turn-table the forks 68, can be swung through a radius of 180 degrees and by means of the pinions 45, the conveyor 40, is shifted in and out relative to the frame 29, the length of the racks 44, while by means of the rack members 78 to raise and lower the swinging section 62, the forks are adjusted up and down the length of said racks to vary the throw of said forks, so that the machine is capable of operation on the maximum of a pile of material at one setting of the truck A.
- 15 The forks 68, are cleaned in their movement automatically at each revolution by extended end 91 of the swinging section 62, as on the full inward stroke and the continued upward movement of the arms 67, 20 the forks 68, will scrape on this extended end 91, of the section 62, and thus the material clinging to said forks will be removed therefrom for the cleaning thereof.

From the foregoing it is thought that the construction and manner of operation of the machine will be clearly understood, and therefore, a more extended explanation has been omitted.

What is claimed is:

- 30 1. A machine of the character described comprising a wheeled truck, a turn table supported thereon, a rearwardly inclined stationary conveyor constructed and arranged upon the turn table, an extensibly 35 slidable conveyor constructed and arranged upon the stationary conveyor, a tilting section on said slidable conveyor, means for adjusting the section, and loading mechanism on said section.
- 40 2. A machine of the character described comprising a wheeled truck, a turn table supported thereon, a rearwardly inclined stationary conveyor constructed and arranged upon the turn table, an extensibly 45 slidable conveyor constructed and arranged upon the stationary conveyor, a tilting section on said slidable conveyor, means for adjusting the section, loading mechanism on said section, means for adjusting the turn 50 table, means for extending the slidable conveyor and means for simultaneously operating the conveyors and loading mechanism.
- 50 3. A machine of the character described comprising a wheeled truck, a turn table supported thereon, a rearwardly inclined stationary conveyor constructed and arranged upon the turn table, an extensibly 55 slidable conveyor constructed and arranged upon the stationary conveyor, a tilting section on said slidable conveyor, means for adjusting the section, slotted guides on the section, bearings on said section, a cranked shaft journaled in the bearings, fork arms connected with the cranks of the shaft and having crossheads slidable in the 60 slotted guides, tine forks on the outer ends of the fork arms and means for simultaneously driving the conveyors and operating the cranked shaft.
4. A machine of the character described comprising a wheeled truck, a turntable supported thereon, a rearwardly inclined stationary conveyor constructed and arranged upon the turn table, an extensibly 65 slidable conveyor constructed and arranged upon a stationary conveyor, a tilting section on said slidable conveyor, means for adjusting the section, slotted guides on the section, bearings on said section, a cranked shaft journaled in the bearings, fork arms connected with the cranks of the shaft and having crossheads slidable in the slotted guides, tine forks on the outer ends of the fork 70 arms, means for adjusting the turn table and means for raising and lowering the 75 swinging section.
5. A machine of the character described, comprising a wheeled truck, a turn-table supported thereon, a rearwardly inclined stationary conveyor constructed and arranged upon the turn table, an extensibly 80 slidable conveyor constructed and arranged upon the stationary conveyor, a tilting section on the slidable conveyor, means for adjusting the section, slotted guides on the section, bearings on said section, a cranked shaft journaled in the bearings, forked arms connected with the cranks of the shaft and having crossheads slidable in the slotted 85 guides, tine forks on the outer ends of the forked arms, means for adjusting the turn-table, means for raising and lowering the 90 swinging section, and means for automatically cleaning the forks at each revolution 95 thereof.

In testimony whereof I affix my signature.

WILLIAM OTTO.
